UNITED STATES PATENT OFFICE.

OSCAR H. JUNG, OF MILWAUKEE, WISCONSIN.

FUSE PLUG.

Application filed May 14, 1925. Serial No. 30,236.

To all whom it may concern:

Be it known that I, OSCAR H. JUNG, a citizen of the United States, and resident of Milwaukee, in the county of Milwaukee and State of Wisconsin, have invented certain new and useful Improvements in Fuse Plugs; and I do hereby declare that the following is a full, clear, and exact description thereof.

This invention relates to fuse plugs.

10 Objects of this invention are to provide a fuse plug in which there is no possibility of an arc forming between the center pin and the outer screw shell irrespective of the initial arc formed during the rupture of the fuse, in which a perfect baffle is provided between the center pin and the outer shell, in which evenly positioned openings are provided adjacent the transparent window of the fuse plug, and in which a passage is provided for the gases along a tortuous or circuitous route through mutilated threads formed between the body of the fuse plug and the outer screw shell.

15

Further objects are to provide a fuse plug of such construction that the transparent window is bowed inwardly to resist the internal pressure, thus permitting the use of a very thin mica or similar material, and in which all of the gases are directed towards the window to insure a complete blacking of the window when the fuse blows.

20 Further objects are to provide a fuse plug which is of simple construction, and in which the parts may be easily assembled.

25 An embodiment of the invention is shown in the accompanying drawings, in which:—

Figure 1 is a longitudinal section through the plug.

Figure 2 is a view of the body portion of the plug detached.

Figure 3 is a view of the thimble or inner portion detached.

Figure 4 is a bottom view of the plug.

Figure 5 is a sectional view taken on the line 5—5 of Figure 1.

Referring to the drawings, it will be seen that the body portion comprises an outer end or head 1 which is preferably knurled to facilitate screwing of the plug into the socket. This body portion is of insulating material such as porcelain, and has a rearwardly extending cylindrical portion 2 which is provided with threads 3. These threads are mutilated to provide gaps 4 at numerous points for a purpose hereinafter to appear.

Further, it will be noted that the shell 2

of the body portion is provided with a pair of diametrically opposed rectangular notches 5.

The thimble or inner baffle member comprises a shell or cylindrical portion 6 (see Figures 1 and 3) which is of lesser diameter than the internal diameter of the shell 2 of the body portion. This cylindrical member is provided with a plurality of notches 7 at its upper end, one of which 7', it is to be noted is larger than the remaining notches and receives the fusible element.

It is to be noted particularly that the upper or outer end of the thimble 6 or inner shell and the adjacent portion of the body part of the fuse are curved so that a mica window 8 positioned therein will be bowed inwardly, as shown in Figure 1, and will be held in this bowed position when the plug is fully assembled. The thimble 6 is of insulating material and is provided with a flange 9 at its outer end and with a pair of rectangular lugs 10 adapted to seat in the notches 5 of the body portion. It is provided further with a tapered rear portion 11 which is apertured to receive the central electrical contact 12, as shown in Figure 1. This central electrical contact is provided with a pair of wings or arms 13 which are pressed outwardly, as shown in Figure 1, to engage the beveled inner surface of the thimble 6 and to thus firmly retain the central electrical contact in position.

An outer metallic shell or threaded ferrule 14 is screwed upon the threads 3 of the body portion. It is to be noted that this ferrule is provided with an inwardly folded rear flange 15. Preferably, this flange is crimped at 15' into the spaces 16 (see Figure 4) formed rearwardly of the lugs 10 in the thimble 6 (see Figure 3). Thus, after the flange is in position, it is securely locked against rotation.

The fusible element comprises a strip 17 of easily fusible material which is attached to the central electrical contact by means of a drop of solder 18 positioned between the arms 13 of such central electrical contact. This drop of solder further reinforces the arms 13 and prevents their inward folding. The fusible element extends outwardly in a slanting manner, shown in Figure 1, towards the member 8, and extends transversely adjacent such window. It is provided with a restricted portion 19 adjacent the window so as to insure its opening at this

point under excessive current. This fusible strip extends rearwardly between the thimble 6 and the shell 2 of the body portion. It folds around one of the lugs 10 and has its rearmost portion seated in one of the depressions 16. It is attached to the shell or metal ferrule 14 by means of a drop of solder 20.

It is to be noted particularly that the fusible element extends around the baffle or inner thimble 6 and consequently an arc cannot be maintained between the central pin or contact 12 and the outer metal shell, as the only path possible would be up over the outer edges of the thimble 6 and then downwardly between the body portion and such thimble, thus insuring complete extinction of the arc formed at the blowing of the fuse.

It is to be noted particularly that the mica window 8 may be made of very thin material as it is bowed inwardly towards the pressure and thus effectively resists such internal pressure.

It is to be noted further that the metal ferrule 14 does not tightly engage the threads 3 of the body portion but engages such threads only on their outer sides.

Further, it will be noted that the thimble 6 is spaced from the inner surface of the body portion 2, as shown in Figure 1. Thus the gases generated by the blowing of the fuse will pass upwardly towards the mica window 8, through the notches 7 and 7' inwardly between the sleeve or thimble 6 and the body portion and then outwardly between the body portion and the threaded shell 14, such gases passing through the gaps 4 in the mutilated threads. Thus the fuse plug is perfectly vented and excessive internal pressure is prevented, the gases passing outwardly to the air in the manner described through a tortuous passage to cool the gases and slow down their rate of expulsion from the device. This avoids a violent blast of highly heated gases and yet prevents excessive internal pressure.

It is to be noted further that the mica window will be completely blackened by the blowing of the fuse due to the proximity of the restricted portion of the fusible element and due to the fact that the gases pass outwardly against this mica window, and then are deflected laterally through the notches 7 and 7' and through the passageways described above. This certain and assured blackening of the mica window indicates with certainty the blowing of the fuse.

It will be seen, therefore, that a very effective type of fuse has been provided which will insure the blackening of the window, which cannot rupture the transparent window, which is vented to the outside air to prevent building up of excessive internal pressures, and which will prevent the main-

tenance of an arc between the central contact and the outer shell.

Although the invention has been described in considerable detail, it is to be understood that the invention may be variously embodied and is, therefore, to be limited only as claimed.

I claim:

1. A fuse plug comprising a body having a rearwardly extending cylindrical portion provided with mutilated threads on its outer side, a thimble having a cylindrical portion positioned with said body portion and spaced therefrom, a center electrical contact carried by said thimble, a threaded metal ferrule screwed upon the mutilated threads of said body portion, and holding said thimble in place, said thimble having notches at the end of its cylindrical portion, and a fusible element extending from said center electrical contact, through said thimble, and between said thimble and body portion to said metal ferrule, whereby the gases incident to the blowing of the fuse will follow a tortuous passage between said body and thimble and between said mutilated threads and ferrule.

2. A fuse plug comprising a body having an apertured head and a rearwardly extending cylindrical portion, a thimble having a cylindrical portion positioned within the cylindrical portion of said body, a transparent member positioned on the inner side of said head across said aperture and clamped in position by the forward end of said thimble, the forward end of the thimble and the adjacent portion of the body being curved to bow said transparent member inwardly to resist internal pressure, a center electrical contact carried by said thimble, a threaded metal ferrule carried by said body portion, and a fusible element connecting said ferrule and contact.

3. A fuse plug comprising a body having an apertured head and a rearwardly extending cylindrical portion having exterior mutilated threads, a thimble having a forwardly extending cylindrical portion positioned within and spaced from the cylindrical portion of said body and having notches at its forward end, a transparent member located on the inner side of said head across said aperture and clamped between such head and the outer end of the thimble, the outer end of the thimble and the adjacent portion of said head being curved to bow said transparent member inwardly to resist internal pressure, a center electrical contact carried by said thimble, a threaded metal ferrule screwed upon the mutilated threads and providing therebetween a tortuous passage and having a rear flange engaging the rear portion of said thimble, and a fusible element extending from said center electrical contact through said thimble and outwardly

between said thimble and body portion to said metal ferrule, whereby a baffle is provided and the blackening of the mica window is assured upon blowing of the fuse.

- 5 4. A fuse plug comprising a body having a rearwardly extending cylindrical portion provided with mutilated threads on its outer side, a thimble having a cylindrical portion positioned with said body portion and spaced therefrom, a center electrical contact carried by said thimble, a threaded metal ferrule screwed upon the mutilated threads of said body portion and providing therebetween

a tortuous passage, and holding said thimble in place, said thimble having notches at 15 the end of its cylindrical portion into which a portion of said metal ferrule is crimped, and a fusible element extending from said center electrical contact, through said thimble, and between said thimble and body portion to said metal ferrule. 20

In testimony that I claim the foregoing I have hereunto set my hand at Milwaukee, in the county of Milwaukee and State of Wisconsin.

OSCAR H. JUNG.
